VENTILATED TABLE

Fate A. Dixon, Durham, N. C., assignor of one-fourth to Ned May and one-fourth to Mike May, both of Durham, N. C.

Application October 14, 1949, Serial No. 121,307

1 Claim. (Cl. 230—241)

1

My invention relates to ventilated tables, for use in playing bridge or the like.

An important object of the invention is to provide a table of the above mentioned character which will discharge air currents upwardly and downwardly, in proximity to the players, to promote their comfort.

A further object of the invention is to provide a table of simplified construction, having means for securely holding the legs to the body of the table.

A further object of the invention is to provide a table of the above mentioned character which is attractive in appearance and cheap to manufacture.

Other objects and advantages of the invention will be apparent during the course of the following description.

In the accompanying drawings, forming a part of this application, and in which like numerals are employed to designate like parts throughout the same,

Figure 1 is a perspective view of a table embodying my invention.

Figure 2 is a central vertical section taken on line 2—2 of Figure 1.

Figure 3 is a horizontal section through the table, taken on line 3—3 of Figure 2 and looking downwardly.

Figure 4 is a similar view taken on line 3—3 of Figure 2 looking upwardly, and,

Figure 5 is a bottom plan view of the table.

The table comprises a hollow body portion or casing 10, including sides 11, a top 12 and a bottom 13. The sides 11 have upper and lower strips or bars 14 and 15 rigidly secured to the same by nails or the like. The bars 14 are arranged in an upper rectangular group and the bars 15 are arranged in a lower rectangular group, as shown. Each bar 14 and 15 has its outer portion rectangular in cross-section to snugly fit into the corners produced by the sides 11, top 12 and bottom 13. The bars 14 and 15 have inner cylindrically curved or vertically convex faces 16. The top 12 also may be nailed or otherwise secured to the bars 14 and sides 11, and the bottom 13 is nailed or otherwise rigidly secured to the bars 15 by nails or the like. The bottom 13 is arranged within the lower edges of the sides 11.

Each side 11 is provided at its longitudinal center with a pair of elongated horizontal slots 17 and 18. The slots 17 are inclined upwardly toward their outer ends, while the slots 18 are inclined downwardly toward their outer ends.

2

These several slots are in free communication with the interior of the casing 10. When the table is intended for use by four persons, as is done in playing bridge, the table is made square and each side will have a pair of elongated slots 17 and 18. It is obvious that the table may be made in any dimensions and that the pairs of slots for each side may be increased as found advantageous.

10 The body portion or casing 10 of the table is supported by legs 19, inserted into the casing at the corners thereof. The adjacent ends of the bars 14, at each corner, provide a socket 20 to receive the leg 19, and the adjacent ends of the bars 15 at each corner form a socket 21, to receive each leg. The leg is inserted upwardly within the sockets 20 and 21 until it engages the top 12. The leg has a snug fit within the sockets so that it will not wobble and will be held against downward displacement by a single screw or nail 22. It is obvious that a highly simplified and strong construction is provided for securing the legs to the casing 10.

The bottom 13 is provided centrally thereof 25 with a circular air inlet opening 23, preferably flaring downwardly and receiving a horizontal rotating fan 24, mounted upon a vertical armature shaft 25 of a motor 26. This motor is mounted upon a bracket 27 having feet rigidly secured to the bottom 13.

In operation, when the motor drives the fan 24, air is forced through the opening 23 into the casing 10, under suitable pressure, and discharges through the elongated slots 17 and 18. The slot 30 17 produces an upwardly directed air current, while the slot 18 provides a downwardly directed air current. These air currents are projected against the player, seated at the table. The bars 14 and 15 fill in the top and bottom horizontal corners of the casing, and the convex faces 16 lead directly to the slots and serve to guide the air streams to the slots.

It is to be understood that the form of my invention herewith shown and described is to be taken as a preferred example of the same, and that various changes in the shape, size and arrangement of parts may be resorted to without departing from the spirit of the invention or the scope of the subjoined claim.

50 Having thus described my invention, I claim:
A table, comprising a casing including sides, top and bottom, horizontal bars secured to the inner faces of each side adjacent to their upper and lower edges, the horizontal bars in each 55 vertically spaced pair having inner vertically

convex faces, the upper bars forming a group and providing sockets at the corners of the casing and the lower bars forming a group and providing sockets at the corners of the casing, each side having elongated substantially horizontal slots arranged between the bars, the convex faces of the bars terminating substantially at the outer walls of the slots, the bottom having a main opening and a fan arranged adjacent to the main opening to force air through the same, and a motor arranged beneath the bottom and mounted thereon and serving to drive the fan.

FATE A. DIXON.
